UNITED STATES PATENT OFFICE

100,120

DESIGN FOR A SOLID FUEL STOVE ASHPIT

Wilfred F. Otis, West New York, Harry H. Haas,
Union City, and John E. Otis, West New York,
N. J.

Application March 27, 1936, Serial No. 61,826

Term of patent 14 years

To all whom it may concern:

Be it known that we, Wilfred F. Otis, a citizen of the United States, residing at West New York, Hudson County, New Jersey, Harry H. Haas, a citizen of the United States, residing at Union City, Hudson County, New Jersey, and John E. Otis, a citizen of the United States, residing at West New York, Hudson County, New Jersey, have invented a new, original, and ornamental Design for a Solid Fuel Stove Ashpit, of which the following is a specification, reference being had to

the accompanying drawing, forming part thereof.

Fig. 1 is a perspective view of a solid fuel stove ashpit showing my new design.

Fig. 2 is a side elevation thereof. The other side of the device is similar to that shown.

We claim:

The ornamental design for a solid fuel stove ashpit, as shown.

WILFRED F. OTIS.
HARRY H. HAAS.
JOHN E. OTIS.
